UNITED STATES PATENT OFFICE.

HENRY ERNEST LLOYD OWEN AND KENNETH HALLIDAY MACARTNEY, OF PORT ARTHUR, ONTARIO, CANADA.

TENT.

Application filed May 5, 1922. Serial No. 558,795.

To all whom it may concern:

Be it known that we, HENRY ERNEST LLOYD OWEN and KENNETH HALLIDAY MACARTNEY, both subjects of the King of Great

5 Britain, and residents of the city of Port Arthur, in the Province of Ontario and Dominion of Canada, have invented certain new and useful Improvements in Tents, of which the following is a full, clear, and

10 exact description.

This invention relates to improvements in tents and more particularly to small tents adapted for tourist and campers' use, and the object of the invention is to provide a

15 tent which may be set up with great ease and rapidity.

A further object is to provide a tent of small size which will have large capacity and in which substantially all the floor

20 space will be available.

A still further object is to provide a tent including a ground sheet, thereby obviating the necessity of specially selected sites or trenching.

25 Another object is to provide a tent of the wall type having a single pole.

Still another object is to provide a tent of small size having full head room at the entrance.

30 Yet another object is to provide a tent of small size having adequate ventilating facilities.

One more object is to provide a tent so constructed that the entrance of draughts

35 at the bottom will be prevented.

At the present time small tents are of two classes, namely bell tents or conical tents and wall tents. The former are supported by a single pole and the roof comes down to and meets the ground at an acute angle, so that considerable space is lost around the edges of the tent and only the central part affords standing room. The wall type of tents are of a form similar to

40 a house with double pitched roof and, while they afford standing room from end to end and render a large amount of the space adjacent the side walls available, they have the disadvantage of requiring two poles.

45 Both forms of tents require elaborate pegging and guying and further are always

draughty, by reason of air entering between the bottom of the side and end walls and the ground. Furthermore, these tents require to be pitched in a carefully selected site or to be externally trenched in order to ensure a dry floor. The time required to pitch either form of tent is considerable and is a very awkward undertaking for one person. Various special types of tents have been proposed from time to time for the purpose of eliminating poles, but these require to be pitched between natural supports such as trees.

55 According to the present invention, the tent provided is so constructed that it may be very easily pitched by one person without the necessity of carefully selecting a site or trenching around the tent to secure a dry floor. The tent when erected presents the advantages of both the bell and wall tents and has the additional advantages of a dry clean floor, freedom from draughts and adequate ventilation.

60 The tent comprises a floor member of suitable waterproof material having at one edge an upturned flange portion to exclude water at the front of the tent and connected at its remaining edges to the back and side walls which in turn are connected to one another. The corners and edges of the floor member 65 are provided with loops for pegging down and the other parts with guy ropes ready attached. All or certain of the walls are of hip construction to provide vertical side walls and at the front of the tent a short ridge is provided extending from the central pole to a point substantially over the front edge of the floor, so as to give a vertical front wall. This ridge, which is comparatively short, is supported from the central pole by means of a gaff, thus eliminating the use of a second pole.

70 In the drawings which illustrate the invention:—

Fig. 1 is a perspective view of the tent set up.

Fig. 2 is a front elevation of same with the flaps closed.

Fig. 3 is a side elevation.

Fig. 4 is a plan view.

Fig. 5 is a development of the tent show-

ing the shape and assemblage of the various parts.

Referring more particularly to the drawings, 11 designates a floor member of any suitable form, preferably rectangular and composed of suitable material, such as waterproofed canvas. One of the edges of the floor, which is to serve as the front, is provided with a narrow flap 12 which in the finished form is turned vertically and forms a sill piece to exclude water at the front of the tent. The sides 13 are attached at their lower edges to opposite edges of the floor 11 and taper slightly away from the floor. In forming the sides, a large notch is cut in each side and the edges 14 of the notch secured together, so that the sides each have a hip construction, clearly shown in Figures 1 and 2, and each present a lower vertical portion 15 and a pair of triangular sloping portions 16 connecting at the ridge formed by the meeting edges 14. The folds or seams 17 between the parts 15 and 16 of each side also form ridges in the set-up form of the tent, as will be clearly seen in Figure 1. The back of the tent may be a simple triangular piece 18, as shown in Figure 5, connected at its base to the back edges of the floor and at its sides 19 to the rear side edges 20 of the tent sides, the meeting of the edges 19 and 20 forming ridges 21 in the set-up tent. It will be understood that the back wall may, if desired, be formed similarly to the side walls. The front of the tent is composed of five pieces, two of which, designated 22, are inverted triangular portions, each connected at a side edge to the front edge of a side wall portion 16 and connected together at their bases 23, as clearly shown in Figures 1 and 3. The connected edges 23 form a ridge projecting forwardly of the apex of the tent in the set up form, while the line of connection of the side wall parts 16 and the front parts 22 constitutes a valley 24. These front portions 22 define a triangular opening extending from the sides of the floor member to the forward end of the ridge 22, which opening is the doorway of the tent. To close this opening and complete the front of the tent, triangular flaps 25 are provided, each secured at one side to the forward side of the front portions 22. These flaps are each at its base 26 more than half the width of the doorway, so that when drawn across the opening they will overlap considerably and form a substantial closure. The flaps are, as is customary, each free at its lower and outer side edges. In order to ensure ventilation and also to provide a rain-shed at the point where the flaps meet the ridge 23, a small triangular hood 27 is provided connected at its apex at the meeting of the front flaps and ridge 23 and at its side edges 65 to the flaps adjacent their line of junction

with the front portions 22. This ventilating flap 27 may be straight or curved on its lower edge and is of such width that it will not interfere with the opening of the flaps. The meeting point of the sides and back is the apex of the tent and is provided with the usual reinforcement 28 having therein a small aperture 29 for the pole spike 30. The same construction may, if desired, be applied at the junction of the parts 22, 25 and 27 but this is not essential.

The four corners of the floor member are provided with strong loops 31 by which they may be pegged down to the ground, and, if desired, the edges of the floor may be provided with additional loops 32 for pegging down. Each junction point of the ridges 14 and 17 is provided with a guy rope 33 and the forward end of the ridge 23 may be provided with a guy rope 34. Additionally, the free corners of the flaps may be provided with loops 35 for pegging. The pole, designated 37, is preferably formed of a number of separable sections, in order to facilitate transportation of the tent in a small space. In addition to the pole, there is provided a gaff 38 adapted to engage at one end in the common meeting point of the parts 22 and 25, that is to say, at the forward end of the ridge 23. The opposite end of the gaff is adapted to be supported on the pole by a runner 39 mounted on the pole. This runner is of a form well known to sailors and is a double eye or figure 8 construction, preferably of rope. One eye is of a size to slide freely on the pole when the device is normal thereto. When, however, the runner is inclined to the pole the eye binds very tightly thereon and prevents the runner sliding. The second eye forms a loop, in which the end of the gaff is received.

The operation of the device is as follows:—

The tent is arranged on the ground so that the floor lies lowermost and also flat on the ground with the doorway facing in the desired direction. The operator then pegs down the corners in succession, taking care to stretch the floor tightly. The operator then puts the top end of the pole through the doorway and into the opening 29 and then raises the pole to vertical position, moving through the doorway as the tent rises. When the pole is in vertical position, the back and side walls of the tent will be tightly stretched between the floor and apex and the downward pressure will hold the pole securely. The operator then places the tip of the gaff in the pocket formed by the junction of the parts 22 and 25 and slips the butt end through the empty eye of the pole runner. The runner is then slid upwardly on the pole until the gaff tensions the ridge 23 between its

outer end and the top of the pole, the butts of the gaff, of course, resting against the pole and being held by the runner which also holds it from sliding down.

5 While the erection of the tent as thus far effected is not complete, it nevertheless presents a very stable structure, which will give shelter and will resist a very considerable amount of wind pressure. To complete the erection, the guy ropes 33 and 34 are stretched out and pegged to the ground at suitable distances from the tent or tied to trees. If the front guy rope is stretched at a suitable angle and the apex 15 of the tent supported by rearwardly extending guy (not shown) to balance the tension of the guy 34, the gaff may be omitted but this omission is not important in any except the smallest tents as the gaff 20 is sufficiently high up to give head room therein. If desired, the edges of the tent may be pegged down between the corners by means of the loops 32. When the tent is to be closed the flaps 25 are drawn across 25 the front and fastened in any suitable way but, when a complete closure is not desired, either or both of the flaps may be pegged out by its free corner at any desired angle, so as to form a rain or wind shelter at 30 the doorway of the tent. When not in use, the flaps may be reefed up in the well known manner to the forward edges of the parts 22. The hood member 27 serves to keep water running down the ridge 23 or 35 driven by the wind from entering between the flaps 25 at the top, where there is no overlapping. In the same way this hood which hangs loosely in folds when the flaps are closed serves to permit egress of warm 40 air at the top of the tent without admitting cold air, rain or snow.

The advantages of the device will be apparent to those skilled in the use of tents. The whole tent may be folded within the waterproof bottom of floor so that no part 45 of the interior need become wet. For this reason, bedding, spare clothing, etc., may be packed in the tent and will be kept dry by the floor thereof. The tent may be very 50 easily and quickly set up by one person on practically any ground that presents itself, thus avoiding the necessity of selecting special ground or suitably spaced trees. The waterproof floor avoids the necessity of 55 selecting ground with a view to proper drainage and also ensures a dry tent floor if the tent must be pitched on wet ground. If the tent is set up for only a short time, such as for one night, guying by means 60 of ropes may be omitted, thus materially reducing the work of setting up and taking down the tent. The absence of numerous guy ropes and tent pegs a short distance away from the tent avoids constant tripping over tent pegs and guy ropes in the

darkness, with which unpleasant experiences most campers are familiar. Where the tents are to be pitched close together, as in a summer colony or military encampment, guy ropes reaching to the ground may 70 be entirely eliminated by connecting the guy ropes 33 of adjacent tents together or to poles set in the ground intermediate the tents. In the same way, the guy ropes 34 and any corresponding back guys may be 75 stretched between tents and poles, so as to give head room all around each tent. The hip formation of the sides gives a wall effect in what is otherwise a bell tent, thus materially increasing the available floor 80 space in the tent and enabling cots to be placed closer to the walls than is possible in a bell or wedge tent. The union of sides, back and floor overcomes the draughting 85 characteristic of tents which many people find objectionable, excludes rain, snow or dust which the wind drives under the walls of ordinary tents, and also effectually excludes insects, reptiles and animals. The formation of a vertical front by means of 90 the ridge 23 eliminates the leakage at the doorway, which is a common defect of bell tents, and gives the advantages of a wedge tent in the matter of head room. Obviously, 95 if desired, the back instead of being formed as shown or in accordance with the sides may be formed in the same manner as the front, that is, with a nearly horizontal ridge in place of a noticeably inclined ridge. It will be observed, however, that in any 100 case the difference between the side and front formations illustrated is largely a matter of degree as the hip of the sides might be supported equally well by gaffs, although, to do so would sacrifice freedom of movement within the tent, unless the sides were formed and the gaffs placed as illustrated for the front. In comparison with the weight or area of canvas and the space occupied by the tent when set up, it is 105 extremely roomy.

Having thus described our invention, what we claim is:—

1. In a tent, a wall comprising a substantially vertical lower portion and a pair 115 of sloping upper portions, meeting the lower portion and one another at three ridge lines converging to a common point within the periphery of the wall.

2. In a tent, a wall comprising three substantially triangular portions forming a pyramidal structure disposed with one of its side surfaces substantially vertical.

3. A tent comprising a substantially pyramidal structure in which a side of the 125 structure is in itself a substantially pyramidal structure disposed with one of its sides substantially vertical.

4. A tent comprising a substantially pyramidal structure in which one of the 130

sides is in itself a substantially pyramidal structure disposed with one of its sides substantially vertical, means to hold said pyramidal side structure in pyramidal form, 5 flaps forming the vertical side of said pyramidal side and a hood extending from substantially the apex of the pyramidal side

toward the base, and covering adjacent edges of said flaps.

In witness whereof, we have hereunto set 10 our hands.

HENRY ERNEST LLOYD OWEN.
KENNETH HALLIDAY MACARTNEY.
